UNITED STATES PATENT OFFICE

FLORENCE L. LE VEQE, OF LOS ANGELES, CALIFORNIA

DESIGN FOR WOMAN'S SOCK

Application filed August 4, 1928. Serial No. 27,701. Term of patent 7 years.

To all whom it may concern:

Be it known that I, FLORENCE L. LE VEQE, a citizen of the United States, and a resident of Los Angeles, Los Angeles County, California, have invented a new, original, and ornamental Design for Women's Socks, of which the following is a specification, reference being had to the accompanying drawings, forming a part thereof.

In the drawings

The figure is a perspective view of a sock constituting the design.

I claim:

The ornamental design for woman's sock, substantially as shown.

FLORENCE L. LE VEQE.
